UNITED STATES PATENT OFFICE.

CHARLES W. MORRELL AND HART H. MCNAUGHTON, OF CHARLOTTE,
MICHIGAN.

HEAD FOR TRIPODS.

SPECIFICATION forming part of Letters Patent No. 658,958, dated October 2, 1900.

Application filed November 7, 1899. Serial No. 736,177. (No model.)

To all whom it may concern:

Be it known that we, CHARLES W. MORRELL and HART H. MCNAUGHTON, citizens of the United States, residing at Charlotte, in the county of Eaton and State of Michigan, have invented a new and useful Head for Tripods, of which the following is a specification.

This invention relates to tripods for supporting cameras, surveying instruments, &c., and has for its object to provide an improved head which may be folded into compact form, so that the legs connected thereto may also fold into a comparatively-small bundle, and thereby facilitate the transportation and storage of the tripod.

To this end the present invention consists in the combination and arrangement of parts, as will be hereinafter more fully described, shown in the accompanying drawings, and particularly pointed out in the appended claims, it being understood that changes in the form, proportion, size, and minor details may be made within the scope of the appended claims without departing from the spirit or sacrificing any of the advantages of the invention.

In the drawings, Figure 1 is a top plan view of the improved head in the set-up position of the tripod. Fig. 2 is a sectional elevation thereof, showing the manner of connecting a camera or other instrument thereto. Fig. 3 is a detail perspective view of the head in its folded position. Fig. 4 is a transverse sectional view of Fig. 3.

Corresponding parts in the several figures of the drawings are designated by like characters of reference.

Referring to the accompanying drawings, it will be seen that the head comprises separate plates 1, 2, and 3, respectively, which are substantially duplicates in form and pivotally or hingedly connected, so as to fold inward and overlap one another. Each plate is of substantially-rectangular form and provided with a lateral extension 4, projecting inwardly from the inner edge of the plate and intermediate of the opposite sides thereof. At opposite ends of the plate are pendent bearing-ears 5. To these ears are pivotally connected the upper ends of the members 6 of the re-

spective legs of the tripod by means of a suitable transverse pivot-pin 7.

The plate 1 is the fixed or stationary member of the head and is provided with bearing-ears 8, which are located at the opposite inner corners of the plate and to which the other plates or members are pivotally connected. The corners of the plates 2 and 3, which are contiguous to the stationary plate, are also provided with bearing-ears 9, which rest upon the respective ears of the stationary plate and are connected thereto by the respective upright pivot-pins 10. By reference to Fig. 2 it will be seen that the plate 2 is mounted directly upon the fixed plate, while the other plate 3 is spaced above said fixed plate by means of a washer 11, so that the plate 2 may be accommodated between the fixed plate and the other plate 3. 70

From the foregoing description it will be understood that the plate 2 is adapted to be folded laterally inward upon the fixed plate 1 and the plate 3 also folded laterally inward and across the top of the plate 2, so that the head may be decreased in size to substantially that of one of the plates. 75

To prevent separation of the plates in the set-up position of the tripod, we provide a thumb-screw 12, which projects upwardly through the extension 4 of the fixed plate and at a point equidistant from the centers of the bearing-ears 8, and the upper projecting portion of the shank of the screw, forming an upstanding pin, is slidably received within arcuate slots 13, formed in the respective plates 2 and 3 and extending in a general direction from the outer edge of the plates to the extremities of the extension thereof, and struck from the ears of the plates as centers. As indicated in Fig. 1, it will be seen that the outer ends of the slots 13 engage against the shank of the thumb-screw 12 in the open position of the head and form stops limiting the outward movement of the hinged plates, and by tightening the thumb-screw the plates may be fixedly held in their relatively-open positions. 90

In the folded position of the head, as illustrated in Figs. 3 and 4 of the drawings, it will be seen that the legs of the plate 2 are folded alongside of the legs of the fixed plate and the legs of the plate 3 fold over in the oppo-

site direction against the outer sides of the legs of the plate 2, so that the legs of the tripod are in contact with one another and form a substantially-rectangular bundle. It will 5 be noted that the lateral extension of the plate 3 or the plate itself is longer than the other two plates, so as to accommodate the legs of the plate 2 between those of the other two plates.

- 10 From the foregoing description it will be seen that the present tripod-head comprises normally - superposed pivotally - connected members which are foldable inwardly one upon the other and in substantially-parallel 15 planes, so that said members may be alined one above the other and received within the same compass in the folded position of the head.

To connect a camera or other instrument 20 to the head of the tripod, as illustrated in Fig. 2 of the drawings, the bottom 14 of the instrument is provided upon its under side with a fixed nut 15 let into the bottom 14 and receiving the upper projecting threaded end of a 25 thumb-screw 12, so that the bottom 14 may rest flush upon the plate 3 and be detachably connected to the head by means of the thumb-screw. As the thumb-screw is fixed against lateral movement upon the stationary plate 30 the head may be folded without detaching the latter from the instrument by simply loosening said thumb-screw to permit of the plates being folded and then again tightening said thumb-screw to hold the plates in their folded 35 position and to prevent accidental detachment of the instrument.

Having thus described the invention, what is claimed, and desired to be secured by Letters Patent, is—

- 40 1. A tripod-head, comprising normally-superposed members of substantially the same shape and size, certain of the members being oppositely disposed and pivotally connected to one of the other members, and also foldable inwardly in opposite directions and in substantially-parallel planes one upon the other.

2. A tripod-head, comprising a relatively-fixed member, and opposite members pivotally or hingedly connected to and foldable inwardly in substantially-parallel planes transversely across the fixed member, one of the foldable members being shorter than the other, and received between the fixed member and the said other foldable member, in 55 the folded position of the head.

3. A tripod, having a head, comprising a relatively-fixed meinber, provided with a leg-standard hingedly connected to the outer side of the fixed member, opposite members pivotally or hingedly connected to and foldable inwardly in opposite directions in substantially-parallel planes transversely across each other and the fixed member, one of the foldable members being shorter than the other,

and received between the fixed member and 65 the other foldable members, in the folded position of the head, and leg-standards hingedly connected to the outer sides of the respective foldable members, the leg-standard of the shorter member being received between the 70 leg-standards of the other members.

4. A tripod - head, comprising a relatively fixed or stationary member having an upstanding pin, and opposite members pivoted or hinged to the fixed member and foldable 75 transversely inward in opposite directions and across the upper face of the fixed or stationary member, and provided with slots slidably receiving the upstanding pin.

5. A tripod-head, comprising a relatively 80 fixed or stationary member, opposite members pivoted or hinged to the fixed or stationary member and foldable inwardly thereupon, each foldable member being provided with an 85 arcuate slot struck from the pivotal connection of the member as a center, and an upstanding pin carried by the fixed or stationary member, located equidistant from the pivotal connections of the members, and slidably received within the slots of both pivotal mem- 90 bers.

6. A tripod-head, comprising a relatively 95 fixed or stationary member, opposite members mounted to fold inward upon the fixed or stationary member, each foldable member being provided with an arcuate slot, and a thumb-screw carried by the fixed or stationary member, and the upper end of the thumb-screw forming a pin which is slidably received within the slots of the foldable members. 100

7. A tripod-head, comprising a relatively fixed or stationary member, and opposite members pivoted or hinged to the upper side of the fixed or stationary member, and foldable transversely inwardly in opposite directions 105 thereupon, one of the foldable members being spaced above the other, and the latter member being received between the former and the fixed or stationary member, in the folded position of the members.

8. A tripod-head, comprising a fixed or stationary member, an upwardly - projecting thumb-screw carried thereby, and opposite pivotally - connected members foldable inwardly upon the fixed or stationary member, and provided with slots slidably receiving the shank of the thumb-screw, the latter projecting at one side of the head and also forming means for connecting with the article to be supported. 115

In testimony that we claim the foregoing as our own we have hereto affixed our signatures in the presence of two witnesses.
